UNITED STATES PATENT OFFICE.

SYLVESTER P. DENISON, OF BELLEVILLE, NEW JERSEY, ASSIGNOR TO
HERMAN BROESEL, TRUSTEE, OF NEW YORK, N. Y.

COPYING TELEGRAPHIC APPARATUS.

SPECIFICATION forming part of Letters Patent No. 498,911, dated June 6, 1893.

Application filed February 1, 1893. Serial No. 460,612. (No model.)

To all whom it may concern:

Be it known that I, SYLVESTER P. DENISON, a citizen of the United States, residing at Belleville, in the county of Essex and State 5 of New Jersey, have invented certain new and useful Improvements in Autographic or Copying Telegraphic Apparatus, of which the following is a specification.

My invention is directed particularly to improvements upon apparatus disclosed in a prior patent, No. 315,391, granted to me by the United States on the 7th day of April, 1885, and its objects are, first, to simplify the transmitting portion of the apparatus in such 15 manner as to permit of the preparation of a transmitting message fillet of the simplest possible form; second, to devise a simple and efficient transmitting arm and circuit connections adapted for use with this improved transmitting fillet; third, the construction of adjustable devices for use in connection with the circuit controlling portion of the transmitter which shall be more delicate of adjustment and of a more practical nature than are 25 the corresponding parts described and shown in the prior patent; fourth, the construction of an improved receiving stylus which will vibrate over the receiving fillet with as little friction as possible and avoid as far as may 30 be, unnecessary abrasion or tearing of the moistened fillet. These several objects are accomplished by the improved mechanism hereinafter described.

In the invention disclosed in my prior patent it was necessary to prepare the transmitting fillet either by the use of a non-conducting ink on a conducting fillet or strip, or a conducting ink upon a non-conducting fillet, the circuit of the transmitting generator being either interrupted or made by such conducting or non-conducting ink over the transmitting line according to the nature of the fillet or transmitting blank used. Such a form of fillet is open to the objection of imperfection in its conducting or non-conducting qualities, and to the further objection of unnecessary care required in its preparation, such as would not naturally be taken by persons ordinarily preparing their messages. In 45 order to overcome this objection I have devised the improved form of transmitting fillet

which is prepared by simply indenting or marking the message, character, sketch, or other information it is desired to transmit into a fillet of yielding non-conducting material by the agency of a pointed stylus of steel, hard wood or the like material and causing the indentations thus prepared to automatically close the circuit through a conducting vibrating key carried by the vibrating 55 arm of the transmitter, the impulses thus transmitted to the receiving station being received through the improved form of receiving stylus as will be hereinafter more fully described.

In order that my invention may be fully understood by those skilled in the art to which it relates, reference is had to the accompanying drawings, in which—

Figure 1 is a side elevational view of my 70 improved form of autographic transmitter showing the transmitting fillet in position. Fig. 2 is a plan view thereof and as seen looking at Fig. 1 from the top toward the bottom of the drawing, the box which contains the impelling mechanism for the fillet being shown as broken away. Fig. 3 is a sectional view taken through Fig. 2 on line $x-x$ and as seen looking from the left hand toward the right hand side of the drawing. Fig. 4 is a detail 75 side elevational, part sectional view, of my improved transmitting needle or stylus and circuit and other connections therefor, a portion of the transmitting fillet being shown in position under the vibrating needle or stylus. Fig. 5 is a side elevational, part sectional view, 80 of my improvement in the adjustable contacting devices which regulate the connection of the transmitting battery and avoid the production of tailings on the receiving stylus. Fig. 6 is a side elevational view of the vibrating receiving arm with the receiving stylus in position resting upon the receiving fillet. Fig. 7 is a plan view of the same parts, the receiving fillet not being in position. Fig. 8 85 is a vertical sectional view taken through the receiving stylus and its sustaining case or holder. Fig. 9 is a perspective view of the improved receiving stylus, and Fig. 10 is a dia- 90 grammatic view illustrating a transmitting instrument at one station, a receiving instrument at a distant station, and the circuit con- 95 100

nections, generators, controlling electro-magnets and transmitting and receiving fillets in position showing also a message in the act of being transmitted and received.

5 Referring now to the drawings in detail: D represents the box of the transmitting instrument which incloses clock controlled mechanism (not shown) for feeding the transmitting fillet F forward through the agency of a 10 feeding roller R and tension roller r.

M represents a permanent magnet one pole of which is secured to some portion of the box D as shown, the other pole thereof being in connection with the rear poles of the electro-magnets C C'.

15 a is a vibrating armature permanently magnetized by the free pole of the magnet M and lying in the magnetic field of the free ends or poles of the magnets C C'.

20 A is a transmitting arm carried by the shaft which supports the armature a, and d d' are adjustable springs connected to adjusting screws for regulating the throw of the lever A.

25 All of the parts so far described are disclosed in my prior patent, there being by preference a transmitter and a receiver at each station, the vibrating receiving arm A' (see Fig. 10) at the receiving station being controlled by a polarized electro-magnet like that shown in Fig. 1.

30 L (see Fig. 10) is the transmitting or electrolytic line over which the message is transmitted, and L' is the main or synchronizing line over which currents of alternating polarity are transmitted by a pole changer P C and battery B' or preferably by any well known equivalent form of alternating current electric generator.

35 F is the transmitting fillet which consists preferably of paper or other pliable or yielding non-conducting material adapted to receive the message which is written upon it with a pointed stylus in the same manner as one would write a message with a lead pencil, the writer simply pressing upon the paper with the stylus with sufficient force to clearly indent the message to be transmitted in the upper face of the fillet as shown by the

40 word "Telegraph" on the transmitting fillet F in Fig. 10. The receiving fillet is prepared by moistening a strip of paper similar to the transmitting fillet with any of the usual well known materials which readily decompose under the action of an electrical current.

45 55 This receiving fillet F' rests on the upper surface of a conducting plate N and is drawn forward by a feed roller controlled by clock mechanism as is the transmitting fillet F (see Fig. 1).

60 Referring now to Figs. 3, 4, and 5, I will describe my improved form of transmitting stylus which is carried by the vibrating arm A of the transmitter T.

65 To the end of the arm A is attached by screws s s' a short metallic bar G in the outer

end of which is located a vertically disposed shoe g having a vertical opening throughout its length in which is situated a sliding needle or stylus j pointed at its lower end and 70 provided with a rounded head at its upper end. Upon the upper end of the rounded head rests a yielding spring k which is attached by screws s' s'' to an adjusting block T carried also by the arm A. Near the outer end of this yielding conducting spring k is a contact point e adapted to contact with a corresponding contact point e' carried by a yielding conducting spring d'' secured to the metallic bar G by a screw s'. Through the 80 free end of this contact spring d extends a screw e'' into the metallic bar G. The several screws, s, s', s'' and e'' are for the purpose of manipulating the adjustment of the parts described. The lower end of the needle or stylus j is of such a nature that as the arm A vibrates and carries with it the shoe g, the needle or stylus will fall into the depressions in the indented message strip or fillet F while the shoe g will ride easily back 85 and forth over the surface thereof, as will be more clearly pointed out in connection with the description of the mode of operation. As the arm A of the transmitter vibrates back and forth it carries with it a contacting point 90 p which alternately strikes against the adjustable conducting contact screw o and non-conducting contact o' carried by a vertically disposed lever F', the lower end of which is pivoted to the box D by a pivot extending 95 into the plate f and its lateral surface rests against a yielding disk x of cloth, felt or other equivalent material.

95 p is a spiral spring and n an adjusting nut, the joint function of which is to regulate the 100 adjustment of the friction between the pivoted portion of the arm F' and the disk f. With such a device and through the agency of the adjustable screw o I am enabled to almost entirely annihilate the tailings sent over 105 the transmitting line from the battery B and to therefore effect a clear and well defined message upon the receiving fillet.

110 My improved form of receiving stylus which is illustrated in Figs. 8 and 9 consists of a 115 conducting wire S' of hardened steel and is surrounded with a coating of paraffine, wax, or other equivalent material. I prefer to make the conducting portion of this stylus of the hardest steel, as I find that with such a 120 stylus the record is but little blurred while with an iron or soft steel stylus it is appreciably blurred. I am unable to account for this difference but such is actually the fact. The stylus S' is placed in a casing or holder 125 K which is provided with an expansible adjustable spring t adapted to force it forward as it is worn away. The conducting portion of the stylus S' is allowed to rest squarely upon the receiving fillet F' and the waxed or 130 cylindrical portion will have a sliding bearing thereon, thereby acting simultaneously as

a lubricant and as a preventive against the abrasure or rupture of the surface of the moistened fillet paper.

The operation of the apparatus is as follows: The message having been indented as before indicated upon the fillet F by a stylus, said fillet and the receiving fillet having been placed in position, shown in Fig. 10, the pole changer P C is set in motion, thereby causing rapid reversals of current from the battery B' to be transmitted over the main line L' through the polarized magnets C C' at the transmitter T and receiver R. The transmitting arm A will therefore vibrate in unison with the receiving arm A'. As the stylus or needle j and shoe g carried by the metallic block G and arm A are vibrated back and forth and as the fillet F is fed forward under the movement of the fillet feeding roller R (see Fig. 1) the stylus or needle j will fall into the depressions each time it passes over any portion of the indented record while the shoe g will ride smoothly back and forth and act as a guide for the needle, as will be clearly understood on examination of Fig. 4. When this needle or stylus j falls into such depressions therefore, the contact points e e' will be united. At the same time as the vibrating arm A is being carried, say from right to left looking at Fig. 10, the contact point p will be in contact with the adjustable contact screw o carried by the pivoted lever F². Consequently an impulse is sent from battery B in the direction of the arrow through the arm F², contact screw o, conductor w', yielding conducting spring d'' (see Fig. 4), contact points e' e, yielding conducting spring k, electrolytic line L to the receiver R, thence through the stylus S', chemically prepared fillet F', conducting plate N, conductor w² to earth at e'. When the arm A of the transmitter reaches its extreme limit and starts back, the circuit is interrupted between the contact screw o and the contact point p carried by the arm. On the return stroke of the arm A the contact p comes into mechanical contact with the insulating point o' and the circuit is interrupted during this entire portion of the stroke, thus allowing the receiving stylus to make a record during one-half of its complete stroke only. I find that for the purpose of obtaining a clear and well defined record the best results are obtained by allowing the transmitting battery to be thus connected through the transmitting line to the receiving stylus during one half only of the complete movements of the vibrating arms A and A' and that tailings and other unnecessary blurrings of the record are completely avoided by this arrangement of parts. It is obvious that any kind of message which can be transmitted, indented or embossed on the message fillet F may be transmitted over the line and received upon the receiving fillet F'. In this way I may transmit sketches, maps, or any type of pictures or information which may be thus placed upon the surface of the fillet.

I do not limit myself to the special form of fillet herein described and shown as it is obvious that the message might be embossed or raised by writing it upon the rear side of the fillet and using the raised portions to make the circuit between the contact points under the influence of the vibrating key or stylus.

I am aware that a transmitting fillet has heretofore been devised of non-conducting material, as paper, with a message indented in its surface, and I make no claims herein after to such a fillet other than as claimed in combination with my improved transmitting apparatus hereinbefore described.

Having thus described my invention, what I claim, and desire to secure by Letters Patent of the United States, is—

1. In an autographic or copying telegraph a transmitting stylus or needle carried by an arm controlled in its movement by electro-magnetic means and having motion in a lateral direction, said needle or stylus being located in a vertically disposed shoe and adapted to move simultaneously in a vertical direction substantially as described.

2. In an autographic or copying telegraph a message blank having the message indented in one face thereof, in combination with a sliding stylus or needle carried by a vibrating arm controlled by electro-magnetic means, said stylus having motion also in a vertical direction and operatively connected with a circuit making and breaking device and to a transmitting battery the circuit making and breaking device being also carried by the vibrating arm, substantially as described.

3. In an autographic or copying telegraph a vibrating transmitting arm carrying a sliding stylus operatively connected with a circuit interrupter also carried by the transmitting arm, in combination with a second circuit interrupter adapted to close the circuit of the transmitting battery during one portion only of its complete vibratory movement substantially as described.

4. A receiving stylus for autographic or copying telegraphs made of conducting material surrounded by a coating of wax or paraffine substantially as described.

5. A receiving stylus for autographic or copying telegraphs consisting of a metal core surrounded by a cylinder of paraffine or wax substantially as described.

6. A receiving stylus for autographic or copying telegraphs consisting of a metal core surrounded by wax or paraffine and inclosed in a case or holder substantially as described.

7. A receiving stylus for autographic or copying telegraphs consisting of a metal core surrounded by wax or paraffine and inclosed in a holder or case and provided with means for forcing it forward as it wears away substantially as described.

8. In an autographic or copying telegraph a message fillet or strip having the message indented or depressed in one of its faces; a vibrating transmitting arm carrying a sliding

shoe and a transmitting stylus having sliding movement through the shoe and operatively connected with a circuit breaker carried by the same arm, the arrangement being such that the sliding shoe carries the stylus over the face of the message and allows it to drop into and rise out of the indentations in the record surface substantially as described.

9. A transmitter for an autographic or copying telegraph having a vibrating arm provided with a sliding shoe adapted to ride over the surface of the message fillet, in combina-

tion with a stylus or needle having sliding movement through the shoe and a circuit breaker having operative connections with the sliding needle substantially as described.

In testimony whereof I have hereunto subscribed my name this 28th day of January, 1893.

SYLVESTER P. DENISON.
